United States Patent Office

Des. 224,235
Patented July 11, 1972

224,235

PORTABLE TAPE RECORDER

Andrew Kainass, Syracuse, N.Y., assignor to
General Electric Company

Filed June 23, 1971, Ser. No. 156,172

Term of patent 14 years

Int. Cl. D14—01

U.S. Cl. D26—14

FIG.1.

FIG.2.

FIG.3.

FIG.4.

FIG.5.

FIG.6.

FIG. 1 is a front elevation view of a portable tape recorder showing my new design;

FIG. 2 is a left side elevation view;

FIG. 3 is a top plan view;

FIG. 4 is a rear elevation view;

FIG. 5 is a right side elevation view; and

FIG. 6 is a bottom plan view.

I claim:

The ornamental design for a portable tape recorder, as shown.
